UNITED STATES PATENT OFFICE.

CHARLES THOMAS MASON, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

IGNITION-DYNAMO.

1,176,476.

Specification of Letters Patent.

Patented Mar. 21, 1916.

Application filed July 28, 1913. Serial No. 781,695.

To all whom it may concern:

Be it known that I, CHARLES THOMAS MASON, a citizen of the United States, residing at Sumter, in the county of Sumter and State of South Carolina, have invented certain new and useful Improvements in Ignition-DYNAMOS, of which the following is a specification, reference being had to the accompanying drawing.

10 This invention relates to dual ignition systems, and particularly to those of the magneto type, and consists of a simplified switching arrangement mounted on the magneto so that either the magneto or a second 15 source of current (such as a battery) may be employed at will.

An object of my invention is to eliminate the separate switch and wiring commonly employed between magneto and battery and 20 the like. It is customary, when used with automobiles, to mount this switch on the dashboard, which necessitates wires from the switch to the battery and to the magneto. These wires often becoming broken 25 or misconnected, are a fruitful source of trouble.

Another object is to employ the same interrupter mechanism for both battery and magneto.

30 A further object is to produce a very simple dual system, including all parts of the same except the battery in a self contained single structure, with only the battery wires to connect.

35 Any form of magneto may be employed. A suitable machine is disclosed in my pending application, Serial No. 732,681 filed Nov. 21st, 1912. As the details of construction of the magneto are immaterial, I shall describe 40 the same only sufficiently to illustrate how my ends are accomplished, the essential features of the system being the switch mechanism and its arrangement in relation to the magneto.

45 Figure 1 is a diagrammatic view showing the arrangement of the various parts of an ignition system embodying my invention. Fig. 2 is a view illustrating the mechanical control for the switch member.

50 Fig. 3 is a view of a complete magneto showing the battery connections.

Like figures of reference denote the same parts wherever they are shown.

1 denotes the shaft of the armature or

rotor of the magneto, or it may be any shaft 55 placed on the magneto for the purpose. This carries an insulated disk 2 supporting the brushes 4 and 5. A brush 6 is carried in the shaft member, but passes through 2 without touching same.

7 and 8 are commutator segments carried by the plate 9 from which they are suitably insulated. 9 is supported by the insulated stud 10, and is arranged to be shiftable in any suitable manner, toward or away from 65 the brushes 4, 5, and 6. The stud 10 is conveniently supported axially of the rotor shaft 1 by means of a suitable casing and in such a manner as to be easily reciprocated. Such support is indicated generally 70 in Fig. 3, the casing housing the commutator parts being either the same casing which houses the interrupter contacts of the magneto or a similar casing located on either end of the machine. The details of this 75 arrangement are immaterial. The switch arm 11 is suitably pivoted to the frame of the magneto as shown at 12 and is operated by the rod 13.

The magneto is provided with the usual 80 primary and secondary windings 14 and 15, and the usual interrupter mechanism indicated at 16 which is operated by the usual cam 17. A condenser 18 is connected in multiple with the primary and interrupter. 85 These parts and their functions are already well known, so I do not describe their arrangement in detail.

The plate 9 being in the position shown 90 in Fig. 1 so that it and the commutator segments 7 and 8 are in contact with the brushes 4, 5, and 6, and a suitable source of current being connected to the wires 19 and 20, current will flow from conductor 19 to segment 7, brush 4, disk 2, brush 5, 95 plate 9, stem 21, and over conductor 22 to one side of the interrupter 16, and the primary winding 14. Supposing the interrupter contacts to be closed as shown in Fig. 1, the current will pass across these 100 contacts to conductor 23, and to the "ground" or frame of the machine indicated at 24, which is connected to the shaft or other member 1 by brush 25 or in any other suitable manner, and from thence to brush 105 6, segment 8, and via conductor 20 to the battery. As cam 17 revolves the interrupter contacts are opened and the current then,

flows through the primary winding 14, thereby inducing current in the secondary 15 and causing a spark in the usual manner at the plug 26.

5 The foregoing describes the system employing the battery as a source of current, this usually being the case when the magneto is being slowly revolved, as when starting the engine. When it is desired to use the current generated by the magneto and 10 cut out the battery, handle 27 may be pushed in one notch thereby moving it from the spring stop 28 where lever 11 is held when battery is employed, to the spring stop 29. 15 This moves plate 9 carrying the commutator, to the left, as shown in Fig. 2, thereby withdrawing the commutator segments 7 and 8 from the brushes 4 and 6, and also withdrawing plate 9 from brush 5. This 20 operation disconnects the battery from the circuit, and the magneto is now free to operate. To stop the magneto current, handle 27 is pushed in to the extreme right-hand spring stop 30, which grounds stem 21 on a suitable contact 31, thereby short-circuiting 25 the primary winding 14 and interrupter contacts 16 and stopping the generation of current.

It will be observed that since the battery 30 commutator is entirely out of contact with the brushes, no mechanical wear takes place when the battery is not actually in use.

With this understanding of the details of 35 my invention, it will be clear that the commutator, as one function, reverses the battery connection with respect to the interrupter and primary winding of the magneto, as the rotor turns through each half revolution, whereby the battery current always 40 flows through the primary winding in direction to be augmented (and not opposed) by the currents being generated by the magneto. The commutator segments are geared to the rotor in proper angular relation so 45 that they pass battery current in phase with the generated electromotive forces or currents. As a second function, combined with the first, the commutator acts in its entirety as a switch to disconnect the battery and 50 stop the machine.

While I have shown my invention embodied in a switch mounted in connection with the usual interrupter casing, on one end of the magneto, I do not wish to confine 55 myself to this location for the switch as it may be mounted anywhere about the magneto. Instead of brush contacts, the switch may consist of spring members suitably operated by any form of rod or lever, it being 60 understood that my invention consists broadly of a combination with the usual magneto, of a switch mechanism mounted on or in connection with the magneto and adapted to be suitably operated thereby.

65 When the switch mechanism is mounted on

the magneto instead of at a remote point, intermediate connections are wholly eliminated as above set forth.

Having thus described my invention what I claim and desire to secure by Letters Patent is—

70 1. An ignition system comprising a dynamo and a battery, an induction coil common to both, said coil being normally connected to derive current from the operation of said dynamo, and a combined commutator and switch driven in synchronism with the dynamo and controlling the connection of the battery with said induction coil so that when its switch contacts are closed the 75 battery current and the dynamo current will augment and not oppose each other.

75 2. An ignition system comprising a dynamo and a battery, an induction coil common to both, said coil being normally connected to derive current from the operation of said dynamo, and a combined commutator and switch driven in synchronism with the dynamo and controlling the connection of the battery with said induction coil with 80 means to close and open the commutator switch contacts to connect and disconnect the battery to and from the dynamo and coil, respectively.

85 3. An ignition system comprising a dynamo and a battery, an induction coil common to both, said coil being normally connected to derive current from the operation of said dynamo, and a combined commutator and switch driven in synchronism with the dynamo and controlling the connection of the battery with said induction coil with 90 means to move the commutator as a unit so as to open its contacts and disconnect the battery from the coil, and a separate contact adapted to be closed by continuing 95 said movement, so as to disable the dynamo.

100 4. An ignition system comprising a dynamo and a battery, an induction coil common to both, said coil being normally connected to derive current from the operation of said dynamo, and a combined commutator and switch driven in synchronism with the dynamo and controlling the connection of the battery with said induction coil with 105 manually controlled means for opening the commutator switch contacts to disconnect the battery at will.

110 5. An ignition system comprising a dynamo and a battery, an induction coil common to both, said coil being normally connected to derive current from the operation of said dynamo, and a combined commutator and switch driven in synchronism with the dynamo and controlling the connection of the battery with said induction coil with 115 manually controlled means for dissociating the battery from said induction coil, and additional means also manually controlled to prevent excitation of the coil 120

125 125

130

by the dynamo after the battery has been so dissociated.

6. An ignition system comprising a dynamo and a battery, an induction coil common to both, said coil being normally connected to derive current from the operation of said dynamo, and a combined commutator and switch driven in synchronism with the dynamo and controlling the connection 10 of the battery with said induction coil with means to shift the commutator into any one of three separate positions, in the first of which the battery is connected with the induction coil through the commutator as described, in the second the battery is disconnected from the induction coil by separation of the contacts of the commutator and the coil is supplied with energy by the dynamo alone, and in the third position the 20 dynamo is disabled.

7. In an ignition system in combination, a dynamo excited primary winding, a battery, interrupter contacts arranged to intermittently short-circuit said primary 25 winding, a commutator driven in synchronism with said dynamo and through contacts of which said battery is connected with said primary winding and said interrupter contacts, means to shift the commutator contacts to disconnect the battery 30 from the winding and interrupter contacts but to leave the dynamo connected therewith, and additional means to shunt circuit said contacts and said winding.

8. In an ignition system a dynamo and a battery having a common induction coil and a combination commutator switch unit through which the battery is connected with the primary winding of said induction coil, 40 said unit being mounted upon said dynamo and having its commutator contacts driven by the rotating element thereof.

9. In combination a magneto electric machine having generating windings, a polarity 45 reversing commutator mounted thereon but normally dissociated from said generating windings and having its elements mounted for combined movement as a switch, together with means to impart said movement thereto.

10. In combination a magneto electric machine having generating windings, a polarity reversing commutator normally dissociated from said generating windings and having 55 an element mounted for axial reciprocating

movement, together with means to reciprocate said commutator element axially, and shunt-circuiting contacts associated with said generating winding and arranged to be closed through the axial movement of the 60 commutator element.

11. In combination a magneto electric machine having a generating winding, a battery, a commutator therefor comprising relatively fixed and movable contacts normally dissociated from the terminals of said generating winding, means to shift the contacts of said commutator out of engagement with each other for switching and circuit controlling contacts for said generating 70 winding operable through the shifting of said commutating contacts.

12. In combination a dynamo excited induction coil, dynamo operated interrupter contacts, and a normally open shunt-circuit 75 for the primary winding of said coil all connected commonly in multiple with each other, together with a battery and a dynamo driven switching commutator through which said battery is adapted to be connected in multiple with the aforesaid elements.

13. In combination a dynamo excited induction coil, dynamo operated interrupter contacts, and a normally open shunt-circuit 85 for the primary winding of said coil all connected commonly in multiple with each other, together with a battery and a dynamo driven commutator through which said battery is connected in multiple with the aforesaid 90 elements and means to disconnect the battery and at will close said normally open shunt circuit, by shifting the commutator.

14. In an ignition system, a dynamo, a battery, a coil, variable circuit connections 95 adapted to produce energization of said coil by the dynamo or by the battery, and means for controlling said circuit connections comprising a switch and a commutator combined in one piece of mechanism mounted as a unit on the dynamo and forming therewith a single self-contained piece of apparatus.

In testimony whereof I hereunto affix my signature in the presence of two witnesses. 105
